UNITED STATES PATENT OFFICE.

GEORGE F. PARKER, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR AN ARTICLE OF HOLLOW WARE.

56,941.

Specification for Design.

Patented Jan. 18, 1921.

Application filed July 19, 1920. Serial No. 397,507. Term of patent 7 years.

To all whom it may concern:

Be it known that I, GEORGE F. PARKER, a citizen of the United States, residing at Newburyport, in the county of Essex and State of Massachusetts, have invented a new, original, and ornamental Design for an Article of Hollow Ware, of which the following is a specification, reference being had to the accompanying drawing, forming a part thereof.

In the accompanying drawing there is shown a representation of a circular plate embodying the new design.

The design comprises an embellished article of hollow ware and, as shown, is embodied in a circular plate, but it will be understood that the application of the design is not limited to this specific form of hollow ware article, as it may obviously be embodied in articles of hollow ware of other configurations and shapes.

What is claimed, is:

The design for an article of hollow ware ornamented substantially as shown and described.

GEORGE F. PARKER.
